Primary Examiner — Jae Liang*Assistant Examiner* — Tia Ruth-Renee Polidori*(74) Attorney, Agent, or Firm* — Nitin Kaushik(57) **CLAIM**

The ornamental design for an electric shaker bottle, as shown and described.

DESCRIPTION

FIG. 1 is a top perspective view of an electric shaker bottle, showing my new design;

FIG. 2 is a bottom perspective view thereof;

FIG. 3 is an exploded view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines in the drawings illustrate the portions of the electric shaker bottle, which form no part of the claimed design.

1 Claim, 9 Drawing Sheets(56)
